UNITED STATES PATENT OFFICE

150,266

DESIGN FOR A CIGARETTE CONTAINER

Joseph B. Stier, New York, N. Y.

Application March 15, 1947, Serial No. 137,636

Term of patent 14 years

(CL. D85—2)

To all whom it may concern:

Be it known that I, Joseph B. Stier, a citizen of the United States of America and resident of the city, county, and State of New York, have invented a new, original, and ornamental Design for a Cigarette Container, of which the following is a specification, reference being had to the accompanying drawing, forming part thereof, in which Fig. 1 is a top plan view of a cigarette container, showing my new design; Fig. 2 is a side elevational view of the same, and Fig. 3 is an end view of the same.

I claim:

The ornamental design for a cigarette container, substantially as shown.

JOSEPH B. STIER.
